US0D1041555S

(12) United States Design Patent (10) Patent No.: US D1,041,555 S
(45) Date of Patent:  Sep. 10, 2024

(54) TYPEFACE

- (71) Applicant: Truist Bank, Charlotte, NC (US)
(72) Inventors: Bianca Berning, Bromley (GB); Rafael Saraiva Soares, Rio de Janeiro (BR)
(73) Assignee: Truist Bank, Charlotte, NC (US)
() Term: 15 Years
(21) Appl. No.: 29/916,115
(22) Filed: Nov. 8, 2023

Related U.S. Application Data

- (63) Continuation of application No. 29/881,808, filed on Jan. 6, 2023, now Pat. No. Des. 1,011,417, and a continuation of application No. 29/777,752, filed on Apr. 8, 2021, now Pat. No. Des. 978,962.
